UNITED STATES PATENT OFFICE.

FREDERICK W. BROWN, OF CAMBRIDGEPORT, ASSIGNOR TO OLIVER WHYTE & CO., OF BOSTON, MASSACHUSETTS.

DRESS-FORM.

SPECIFICATION forming part of Letters Patent No. 399,181, dated March 5, 1889.

Application filed August 10, 1888. Serial No. 282,445. (No model.)

To all whom it may concern:

Be it known that I, FREDERICK W. BROWN, a citizen of the United States, residing at Cambridgeport, in the county of Middlesex 5 and State of Massachusetts, have invented certain new and useful Improvements in Dress-Forms; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a vertical section of dress-form provided with my improvement. Fig. 2 is a horizontal section on line 1 1 of Fig. 1. Fig. 3 is an under side view of one of the adjusters provided with notches, as described; Fig. 20 4, a similar view of the same without said notches. Fig. 5 is a top view of the flanged slide provided with projections, as set forth; and Fig. 6, a similar view of same without said projections.

25 The nature of my invention is defined in the claims hereinafter presented.

In the drawings, A denotes the standard for sustaining the dress-form, it being supported at its lower portion in a suitable stand, in 30 which it can be raised or lowered and clamped in position at the desired height in the usual way. The standard is formed in two parts, x y, coupled together at z, each portion having a screw-thread, v or w, formed on its upper part. A knob is secured to the top of the standard, as represented.

40 B is the dress-form, made in sections, each section being sustained by rods C, connected to the form and to a head, D, applied to the standard, so that it can turn thereon, said head resting at its bottom on the coupling z.

E is a flange or collar fixed to the standard, below which and so arranged as to turn on said standard is a head, F, which rests on a 45 bearing, H, on the standard, and to said head is pivoted a series of adjusters, G, there being as many of said adjusters as there are sections to the form. Each adjuster is represented as made of a single piece of flat strip 50 metal, it having a straight portion, a, a curved portion, b, fastened at its end to the

part a, and an eye, c, the latter being pivoted, as shown, to the head F. The outer surface of the curved part b of each adjuster bears against the sectional portion of the waistband of the form, and is arranged between ears f f projecting therefrom. A pin, g, sustained in the said ears f f, serves to connect the said curved portion of each adjuster to the waistband-section. The pin g may, however, be dispensed with. The parts a of each adjuster is provided with notches h, as shown, to receive the projections i, formed on the flange-slide K, in order to admit the said part a to an opening, k, formed in said slide to receive it, and thus connect said adjuster to the slide, the projections i extending over or upon the upper surface of the part a, as represented. In some cases the adjusters G are unprovided with the notches h in the part a and 65 the slide K formed without the projections i, (see Figs. 5 and 6,) the pressure of the form-section toward the standard being usually sufficient to keep the part a of the adjuster against the bottom of the opening k in the 70 slide.

The slide K is arranged on the standard so as to be movable vertically thereon, and is connected by rods m with a flanged nut, L, applied to the screw-thread w of the standard. So rods n also connect the slide K to another slide, M, arranged below it on the standard, and to the slide M, and to each section of the skirt-frame braces o are pivoted. The edge bands of each section of the skirt-form are 85 connected by links pivoted thereto and to each other in the usual way.

To the screw-thread v of the standard a nut, N, is applied, as shown, and extending downward from said nut is a sleeve, p, provided at 90 its lower end with a bearing, q, on which is arranged so as to turn thereon a flanged sleeve, O, which is connected with a series of neck-adjusters, P, of the same or similar construction as the adjusters G, they being also 95 connected to the neck portion of the waist-form sections and pivoted to a head, Q, sustained on the standard and arranged to turn thereon in essentially the same manner as the adjusters G are connected to the waistband-sections and to the head F.

100 By revolving the nut N the flanged sleeve

O will be raised or lowered and the adjusters connected thereto caused to enlarge or diminish the size of the neck portion of the form, thus admitting, as will be seen, of an independent adjustment of said portion, as may be desired.

In revolving the dress-form around the standard to enlarge or diminish it in size the heads Q, D, and F will turn on the standard 10 with the form, as will also the slides K and M and the nut L, which, being connected to each other by the rods m n, will turn together, and as the nut L rises or lowers on the screw w, so likewise the slides K and M will 15 rise or fall on the standard and move the adjusters G and braces o, so as to expand or contract the form in its waist and skirt portions. In the movement of the form about the standard the flanged sleeve O will also 20 turn with it about the bearing q of the sleeve p, and consequently the adjusters P will not be moved on their pivots to change the size of the neck portions of the form, the adjustment of which is effected by means of the nut 25 N, as hereinbefore set forth.

The invention herein described is an improvement on that represented in the United States Patent No. 385,725, granted July 10, 1888, to Patrick Quinn, and to myself as 30 signee, it being simpler in construction and less expensive to manufacture, the slotting of the standard and arrangement therein of the rod B, provided with a head at the top to bear in the knob and at bottom with prongs 35 to extend through slots in the standard, also

the arms h and the slotted arms i, being dispensed with, the operative devices in this case being arranged wholly outside of the standard, as described and represented.

Having described my improvement, what I 40 claim in a dress-form made in sections and supported on a standard essentially as represented is—

1. The flanged slide K, provided with openings k, combined with the nut L, connected 45 to the standard, as shown, the rods m, connecting said nut and slide, the head F, supported on the standard, the adjusters G, pivoted to the head and connected to the flanged slide and to the form-sections, arranged, connected to each other, and supported essentially as shown and set forth.

2. The combination of the dress-form made in sections, the standard A, the nut L, and 50 slides K and M on the standard, the head F, also on the standard and between the nut L and slide K, the rods m, connecting the nut L and the slide K, the rods n, connecting the slides M and K, the rods o, connecting the slide M with the dress-form sections, the adjusters G, pivoted to the head F and loosely 55 connected to the slide K, and the dress-form sections, as set forth.

In testimony whereof I affix my signature in presence of two witnesses.

FREDK. W. BROWN.
